LIBRARY DESK UNIT

Stewart J. Milne, St. Paul, Minn., assignor to Brown & Bigelow, St. Paul, Minn.

Application April 6, 1954, Serial No. 29,885

Term of patent 7 years

(Cl. D74—1)

To all whom it may concern:

Be it known that I, Stewart J. Milne, a citizen of the United States, residing in St. Paul, county of Ramsey, and State of Minnesota, have invented a new, original, and ornamental Design for a Library Desk Unit, for which the following is a specification, reference being had to the accompanying drawings forming part thereof.

The dominant features of the design reside in the portions shown in full lines.

I claim:

The ornamental design for a library desk unit, as shown and described.
